UNITED STATES PATENT OFFICE.

KIRKLEY HYDE, OF LOWELL, MASSACHUSETTS, ASSIGNOR OF THREE-FOURTHS TO JAMES W. BENNETT, ALBERT M. MOORE, AND FREDERICK TAYLOR, ALL OF SAME PLACE.

WOOD-RIM PULLEY.

SPECIFICATION forming part of Letters Patent No. 309,143, dated December 9, 1884.

Application filed May 12, 1884. (No model.)

To all whom it may concern:

Be it known that I, KIRKLEY HYDE, a citizen of the United States, residing at Lowell, in the county of Middlesex and Commonwealth of Massachusetts, have invented certain new and useful Improvements in Wood-Rim Pulleys, of which the following is a specification.

My invention relates to that class of wood-rim pulleys in which the ends of the middle or foundation fellies engage directly with the outer ends of the spider-arms; and it consists in providing the outer ends of the spider-arms with wedge-shaped ledges and with abutments, and in shaping the ends of the foundation-fellies to receive and fit said ledges and abutments, for the purpose herein specified.

In the accompanying drawings, Figure 1 is a side elevation of such a pulley, a part of the lugs or outer fellies being broken away to show the ledges and abutments at the ends of the arms and the recesses in the ends of the foundation-fellies. Fig. 2 is a central cross-section of the same on the line *xx* in Fig. 1.

A is a metallic spider, consisting of the hub *a* and the arms *a'*, of any usual construction, except that the outer ends of the arms are each provided on each edge thereof with a wedge-shaped ledge, *a''*, substantially as shown in another application filed herewith, except that, whereas in said other application the outer inclined faces of the ledges of each arm meet at the extreme outer end of the arm, and whereas the inner faces of the ledges are inclined from the arm proper, in this application the ledges are each provided with two abutments, *a''*, one on the outer and one on the inner face of the ledge. Each of these abutments has one face that is about parallel

with a plane in which the axis of the spider *4c* lies, and which passes through the center of the arm carrying the abutments. The outer end of the arm is a plane which connects two outer abutments at right angles to the center line of said arm. The middle or foundation 45 fellies, *B*, are each provided at each end with a notch adapted to receive one of the wedge-shaped ledges *a''*, and are otherwise shaped to fit against the abutments and to reach over the outside of the end of the arm and meet the 50 adjacent foundation-felly at the middle of said arm. Each middle felly should fit so closely between two adjacent arms as to require considerable force to press it into place. When the middle fellies are in place, they form a 55 foundation, to which the outer fellies are then secured by screws or nails and glue, in the usual manner.

In the above-described construction it will be seen that any shrinking of the wood of the middle felly will cause its ends to pinch the ledges more closely, and the abutments will prevent the wedge-shaped ledges from working or being crowded into the fellies far enough to split the same.

I claim as my invention—

The combination of a metallic spider, having the outer ends of its arms provided with wedge-shaped ledges and with abutments, and the foundation-fellies having their ends provided with notches to fit such ledges, and otherwise adapted to rest against said abutments and be retained in position thereby, as and for the purpose specified.

KIRKLEY HYDE.
